UNITED STATES PATENT OFFICE

2,633,590

CLEANING AND SCRUBBING DEVICE

Bernard A. Mitchell, Chicago, Ill.

Application October 8, 1948, Serial No. 53,409

3 Claims. (Cl. 15—131)

1

This invention relates to an improvement in a cleaning and scrubbing device, and more particularly to such a device which is fountain operated.

One of the objects of this invention is to provide a compact fountain type operated cleaning and scrubbing device which may be easily handled by the housewife or operator in a standing position for effectively cleaning rugs, carpets and the like, directly on the floor surface of the home.

Another object of this invention is to provide a simple, inexpensive and compact device for cleaning rugs, carpets, floors and other surfaces, which is so constructed and arranged that a cleaning fluid is fed to the brush and the amount of cleaning fluid to be dispensed is under the control of the operator, said cleaning fluid passing through the brush body and on to the surface to be cleaned.

In cleaning rugs, carpets and the like, it is the present practice to either send them to cleaning establishments operating for that purpose, which is an inconvenience and costly, or to clean the rug directly on the floor by a person getting down on his hands and knees and by means of a hand held brush laboriously scrubbing the rug, which requires time and physical exertion, or else to bring into the home specially for that purpose heavy and cumbersome electrically operated cleaning devices, which are expensive and require expert handling.

The purpose of this invention is to provide a compact device which is light in weight, inexpensive to manufacture, which may be readily and easily handled and manipulated with minimum effort by the housewife to effectively clean the rug or carpet directly on the floor of the home while in a standing position, and which may be kept in the home and conveniently used. This device may likewise be used for cleaning floor or other surfaces as well.

Other objects will become apparent as this description progresses.

In the drawings:

Fig. 1 is a side view of my cleaning and scrubbing device.

Fig. 2 is a longitudinal sectional view of the handle portion showing the actuating mechanism.

Fig. 3 is a perspective view of the brush member and showing the flare of the brush bristles.

2

Fig. 4 is a perspective view showing the lower container portion of the device, as well as the brush, with some of the bristles eliminated for purposes of clarity.

5 Fig. 5 is a rear view showing the container and brush member.

Fig. 6 is a cross sectional view taken on line 6—6 of Fig. 5 showing particularly the mechanism for controlling the flow of the liquid.

10 Fig. 7 is a cross sectional view showing the upper funnel shaped portion of the tank, and

Fig. 8 is a cross sectional view of a modified form of construction showing another method of securing the brush to the container.

15 The device comprises a container, generally indicated at 10, for containing the liquid cleaning fluid, a handle, generally indicated at 12, which supports a trigger actuating mechanism, generally indicated at 14, for operating a valve, generally indicated at 16, to control the flow of the liquid. The brush member, generally indicated at 18, is supported and carried by the container.

More specifically, the top of the container 10 is shaped to provide a depressed or funnel shaped

25 section 20 having a depending neck 22 which forms the entrance to the container. A removable closure 23 fits into the neck and closes the opening. The top of the container is inclined at an angle as shown at 21 in Fig. 1, and together

30 with the funnel entrance enables the container to be filled without spilling when the top of the container is positioned substantially parallel to the floor, as shown in Fig. 7. The bottom 24 of the container is welded or otherwise permanently secured as at 25 to the container walls. The bottom 24 is at an inclined angle with respect to the vertical axis of the container, so that the bottom on which the brush is supported will be substantially parallel with the floor when the device is

35 used. The bottom is shaped to provide a rectangular shaped raised or recessed section 26 which has an angularly inclined bottom supporting wall 27 provided with an opening 28. Secured at right angles to said inclined bottom wall 27 is a hollow

40 extended tubular handle 29 which has an internally threaded portion 30 at the lower end thereof into which is screwed the threaded plug 31, having an internal bore 32 and a flanged head 33.

45 The top entrance of the bore is tapered as at 32a to form a seat for the valve to be described. A

gasket 34 is interposed between the flanged head and the underside of the inclined wall 27. The tubular handle 29 extends through an opening 35 in the top of the container and is firmly supported by the sleeve 36 formed in the top of the container. In operating the device the handle is positioned at an angle as shown, and the brush bristles are substantially parallel to the floor.

Slidably supported within the hollow handle is the trigger actuating mechanism, generally indicated at 14, adjacent the upper part of the handle for convenient use by the operator while in a standing position. Same comprises a substantially inverted L-shaped member 37 which is supported by a pair of transverse pins 38 fastened thereto and riding in slotted sections 39 formed on the opposite sides of the hollow handle. The leg 40 of the L-shaped member extends through a cutout 41 in the tubular handle. Said cutout is covered by a cover plate 42 which is fastened to the handle as at 43, and which has a slotted opening 44. The slotted sections 39 serve to limit the movement of the trigger mechanism.

The inverted L-shaped member 37 is secured as at 45 to a rod 46 which is supported inside the hollow handle. The rod passes through a guide 47 secured inside the handle. The valve member, generally indicated at 16, comprises an inverted truncated cone shaped valve 48 which is secured to the end of the rod 46 and seats on the tapered portion 32a of the plug 31 to close the bore 32.

An opening 49 is provided in the hollow handle stem adjacent the valve 48 to permit the liquid cleaning fluid 50 in the container to flow by gravity and pass from the container into the lower portion of the handle and the bore 32 if said valve 48 is unseated or raised.

The upper portion of the handle stem supports a transverse pin 51 on which is secured a coiled spring 52. The opposite end of the spring is coiled around an extension 53 on the end of the L-shaped actuating member 37, and the spring normally urges the actuating member downwardly so that the rod 46 is likewise urged downwardly, seating the valve 48 and closing the outlet bore 32. When the actuating member 37 is elevated or raised by the finger or hand engaging the portion 40 against the tension of the spring 52, the rod 46 will move upwardly unseating the valve 48 and allowing the cleaning fluid to flow by gravity and pass from the container through the handle opening 49 into the bore 32 and downwardly through the brush bristles, to be presently described.

Permanently secured to the lower end of the container is a skirt portion 54 which forms a holder for the brush. The skirt portion comprises a pair of side walls 55 and 56 and an end wall 57, all of which have an inverted bead 58. The skirt has a hinged end wall 59 having a latching end 60 which engages the rolled edge 57a of the side wall 56 to lock therewith.

The brush, generally indicated at 18, has bristles 61 supported throughout by the brush head 62, and has a plurality of openings 63 in the brush head. The bristles forming the outside sides and ends of the brush are flared outwardly and extend beyond the limits of the brush head and holder to permit the bristles to reach the corners and sides of the floor or rug surfaces to be cleaned. Secured on the top surface of the head is a rubber gasket 64. The brush head has a continuously formed groove 75

65 on the side and end wall by which it is slid into the bead 58 of the skirt and where same removably supports the brush. After the brush is positioned within the skirt, the end wall 59 is locked in place and the brush will be retained in position until it is desired to have same removed and replaced, which may be done quickly and easily.

Around the lower end of the container 10 there is secured a rubber bumper member 66 and a similar bumper member 69 may be supported in the channel 67 of the skirt portion.

After the cleaning fluid passes through the valve bore 32, it enters the apertures 63 in the brush head and flows therethrough among the bristles saturating same and then onto the rug or floor surface. The gravity flow of the liquid cleaner may be easily controlled by the trigger actuating mechanism. The unit is light in weight and very compact and may be readily moved over and about a carpet or floor surface in the same manner that a hand brush is moved when applied by a person on his hands and knees. However, with this invention the cleaning is done by the operator standing upright, with less effort and without soiling the hands or clothes. The flow of the fluid to the brush and floor is readily controlled. I have found that rugs, carpets, floors and the like may be effectively cleaned in less time and with less effort than is now possible by the conventional methods. The device has few parts, is comparatively inexpensive to manufacture and yet very efficient.

35 In Fig. 3 I show a modified form of supporting the brush. In all other respects the device is similar to that previously described. Extending through the brush head 70 are a plurality of threaded screws 71 which engage the bottom wall 72 of the container. To remove the brush the screws 71 are unthreaded. The brush head 70 has a continuous groove 73 which supports a rubber molding 74 which acts as a bumper.

40 It will be understood that various changes and modifications may be made without departing from the spirit and scope of my invention.

I claim:

1. A device of the character described comprising a tubular handle having an open lower end and a port opening thereat, a container adapted to contain fluid surrounding the lower portion of said handle and communicating with said port opening, said container having a bottom wall with an opening therein, the said handle being connected to said bottom wall at said opening, a brush having a head with a plurality of openings therein and secured in abutting relation to the underside of said bottom wall, and valve means within said handle for controlling the flow of fluid through said port opening.

2. A device of the character described comprising a tubular handle having an open lower end and a port opening thereat, a container adapted to contain fluid surrounding the lower portion of said handle and communicating with said port opening, said container having a bottom wall with an opening therein, said handle being connected to said bottom wall at said opening, said container having a skirt portion depending from the bottom wall of the container, a brush having a head with a plurality of openings therein and in abutting relation to the underside of said bottom wall and received within said skirt portion, and valve means within said handle for controlling the flow of fluid through said port opening.

3. A device of the character described comprising a tubular handle having an open lower end and a port opening thereat, a container adapted to contain fluid surrounding the lower portion of said handle, said container having a bottom wall with an opening therein and formed with an inwardly recessed section, said handle being connected to said recessed section at said opening, said container having a skirt portion depending from the bottom wall of the container, a brush having a head with a plurality of openings therein and received within said skirt portion with said head abutting the underside of said bottom wall.

BERNARD A. MITCHELL.
